UNITED STATES PATENT OFFICE.

OTTO PETERMANN, OF GROTON, NEW YORK, ASSIGNOR TO STANDARD TYPEWRITER COMPANY, OF GROTON, NEW YORK, A CORPORATION OF NEW YORK.

KEYBOARD.

1,081,142.

Specification of Letters Patent.

Patented Dec. 9, 1913.

Application filed January 17, 1911. Serial No. 603,121.

To all whom it may concern:

Be it known that I, OTTO PETERMANN, a citizen of the Republic of Switzerland, and a resident of Groton, county of Tompkins, 5 and State of New York, have invented certain new and useful Improvements in Keyboards, of which the following is a full, clear, and exact description.

This invention relates more particularly 10 to the key-levers and means for supporting the same of front-strike foldable typewriting machines.

The primary object of the invention is to provide a machine in which each key-lever 15 may be formed as a single piece from sheet metal, and the said key-lever so made that it may be suspended from a support and its bearing portion formed so as to provide an extended bearing surface for the key-lever 20 to prevent all liability to sidewise motion.

Another object of the invention is to provide a key-lever which may be stamped from sheet steel or other metal with a minimum amount of waste, and which may be 25 readily and easily made to permit the same to be properly supported on the machine frame.

A further object of the invention is to provide key-levers which may be supported 30 in groups along transversely-extending rods and which have integral means for spacing the same apart in groups, and to provide means whereby the key-levers may be yieldingly forced in one direction and have their 35 inner ends connected to the type-bars to operate the same.

With these and other objects in view, the invention will be hereinafter more particularly described with reference to the accompanying drawings, which form a part 40 of this specification, and will then be pointed out in the claims at the end of the description.

In the drawings, Figure 1 is a longitudinal section, partly in elevation, of one form 45 of machine embodying my invention. Fig. 2 is a fragmentary plan view, partly in section, showing how the key-levers are constructed and supported. Fig. 3 is a detail 50 elevation of the key-lever blank; and Fig.

4 is a perspective view of one of the key-levers.

The frame 10 may be of any suitable construction and may have a vertically movable and foldable support 11 on which a carriage 12 is mounted to move transversely of the machine. A platen 13 is mounted on the carriage to move therewith, and for letter-spacing a suitable escapement mechanism is provided including a rack 14 which is engaged by dogs mounted upon the support, there being a suitable propelling mechanism as at 15, for forcing the carriage in one direction. The escapement mechanism may be operated by a rocking frame 16 which may be pivoted, as at 17, and arranged to rock the frame are bell-crank levers 18, the outer ends of which are connected to a universal bar 19. The parts thus described may be of the usual or of any preferred construction.

A plurality of transversely-extending rods 20, 21 and 22 are suitably supported between the sides of the frame 10, and mounted on said bars are key-levers 23. 75 These key-levers are arranged in groups. As shown, there are three groups, each group being supported on one of the transversely-extending rods and each key-lever has its inner end 24 located under the universal bar 19 and has a projecting portion or lug 25 in which is an aperture 26. A link 27 connects the lug 25 by engagement with the aperture 26 at one end and an aperture 28 in a lug or projecting part 29 80 of the type-bar 30. The type-bars 30 are pivoted at 31 to a bracket or brackets 32 suitably supported on the rear part of the machine frame, and each type-bar has a type-head 33 on which may be a plurality 90 of characters as shown, and which, when the key-levers are forced downward for printing, will be forced upward against the work sheet carried by the platen 13.

The key-levers 23 have a substantially 95 horizontally disposed body provided with a portion 34 and an angular portion 35, and at one end of the horizontal portion 34 of the body is a part 36 which extends upward and has a finger piece or key 37.

Each key-lever has a lug 38 and connected to each lug is an independent spring 39, one end of which is connected to said lug, and the other end thereof to a transverse bar or plate 40, said spring tending normally to hold each key-lever in a horizontal position. The key-levers each have an integral suspending head or member 41. This head has a bearing part 41^a which projects upward 10 from the upper edge of the key-lever body and in said part is an aperture 42 adapted to fit over one of the transverse bars 20 to 22 according to the grouping of said levers. An integral reach or tie bar 43 extends outward and laterally from the front edge of the bearing part 41^a, and at the end of said reach bar 43 is a lug 44 in which is an aperture 45.

In forming the blank of the key-lever, the 20 bar 43 is stamped so as to lie substantially parallel with the part 34 of the key-lever body, and said bar is then bent or formed at substantially right angles to said body and the lug 41, and the part 44 is bent at right 25 angles to the bar 43 at a point, as at 46, so as to lie parallel with the bearing part 41^a and so that the openings 42 and 45 will be in alinement. By this means, the key-lever may be readily made with a minimum 30 amount of waste and the bar and bearing parts 41^a and 44 serve to provide means whereby the key-levers may be spaced in groups along the transverse bars or rods 20 to 22, it being only necessary to see that 35 the outer key-levers are properly spaced, as by the collars or sleeves 47 held on the ends of the said rods as shown best in Fig. 2.

While I show the invention as applied to a folding typewriter, it will be understood 40 that the invention may be applied to the usual or any preferred form of machine, and while I show certain features of such a machine and particularly the frame, the universal bar and its connection with a part of 45 the escapement mechanism, such features are not claimed herein, but are covered in other pending applications filed by me.

From the foregoing, it will be seen that a simple and efficient key-lever is provided 50 which may be stamped as a single piece from sheet metal; that said key-lever has an extended bearing surface which serves to space the key-levers apart; that simple means is provided whereby the key-levers may be suspended from supports extending transversely of the machine; and that simple means is provided whereby the key-levers may be readily operated and connected to the type-bars.

60 Having thus described my invention, I claim as new and desire to secure by Letters Patent:—

1. In a typewriting machine, the combination with a plurality of transversely-extend-

ing supporting rods, of a plurality of key-levers suspended from said rods in groups and each key-lever having its body portion formed with an integral suspending head intermediate its ends and comprising an upwardly-projecting bearing part, an integral 70 reach bar arranged at right angles to said part, an integral bearing portion at right angles to said reach bar and in alinement with the first-mentioned bearing part, said alined bearing parts having apertures there- 75 in to fit the rods and arranged to bear directly against the bearing parts of the key-lever next adjacent thereto.

2. In a typewriting machine, the combination with a support, of key-levers each 80 provided with a horizontally arranged body having an integral suspending head intermediate the ends and extending laterally on one side only of the body of the lever.

3. In a typewriting machine, the combination with a support, of a plurality of key-levers each provided with an integral suspending head located above the body of the key-lever intermediate the ends and extending on one side only of said body, said head 90 having spaced bearing parts and a bar connecting said parts at the vertical edges thereof.

4. In a typewriting machine, a key-lever having a substantially horizontally-extending body portion, a bearing part extending from one edge and intermediate the ends thereof and provided with an aperture, an integral reach and spacing bar located at the front edge of said bearing portion and 95 at right angles thereto, and a lug at right angles to the reach bar and having an aperture in alinement with the aperture of the projecting part.

5. In a typewriting machine, a key-lever 105 provided with a suspending head intermediate the ends of said lever and having spaced and apertured integral bearing parts in substantial alinement.

6. In a typewriting machine, a key-lever 110 having an integral suspending head located above the body and provided with spaced bearing parts and a bar connecting said parts and extending on one side only of the body.

7. In a typewriting machine, a key-lever having a horizontally disposed body and provided with an integral suspending head intermediate its ends and comprising vertically disposed and spaced bearing parts 120 having apertures to fit over a support, and a bar connecting said parts and extending on one side only of said body.

8. In a typewriting machine, a key-lever stamped in a single piece from sheet metal 125 and comprising a substantially horizontally disposed body portion, a vertically project- ing bearing part having an aperture and ex-

tending from one edge of the body intermediate its ends, an integral reach bar arranged at right angles to said bearing part, and an integral lug formed at right angles to the reach bar at one end thereof and having an aperture in alinement with the aperture of the first-mentioned bearing part.

This specification signed and witnessed this 6th day of January A. D. 1911.

OTTO PETERMANN.
